UNITED STATES PATENT OFFICE

HARRY J. SCHMITT, OF ST. ALBANS, NEW YORK, ASSIGNOR TO WILLIAM R. NOE & SONS, A COPARTNERSHIP, OF NEW YORK, N. Y.

DESIGN FOR A PEDESTAL FOR ELECTRIC LAMPS

Application filed March 30, 1927. Serial No. 21,403. Term of patent 7 years.

To all whom it may concern:

Be it known that I, HARRY J. SCHMITT, a citizen of the United States, residing at St. Albans, in the county of Queens and State of New York, have invented a new, original, and ornamental Design for a Pedestal for Electric Lamps, of which the following is a specification, reference being had to the accompanying drawing, forming part thereof, in which—

Fig. 1 is a top plan view showing my new design;

Fig. 2 is a side view.

I claim:

The ornamental design for a pedestal for electric lamps as shown.

HARRY J. SCHMITT.
